UNITED STATES PATENT OFFICE.

POMPIE LEE ROBERTSON, OF MAYBEURY, WEST VIRGINIA.

TRAIN-OPERATED MECHANISM FOR OPENING AND CLOSING DOORS.

No. 870,689.

Specification of Letters Patent.

Patented Nov. 12, 1907.

Application filed July 3, 1907. Serial No. 382,035.

To all whom it may concern:

Be it known that I, POMPIE LEE ROBERTSON, a citizen of the United States, residing at Maybeury, in the county of McDowell and State of West Virginia, have 5 invented certain new and useful Improvements in Train-Operated Mechanism for Opening and Closing Doors; and I do declare the following to be a full, clear, and exact description of the invention, such as will enable others skilled in the art to which it appertains to make and use the same.

This invention has relation to new and useful improvements in train operated mechanism for opening and closing doors, and particularly mine doors, and has for its object to provide a door with means whereby 15 it may be opened by the weight of an approaching train or other wheeled vehicle adapted to run on a track as it nearly reaches the door, and then to close the door after the passing object has passed under the same.

With the foregoing and other objects in view, the 20 invention consists of certain novel features of construction, combination and arrangement of parts, as will be more fully described and particularly pointed out in the appended claims.

In the accompanying drawings,—Figure 1 is a view 25 in side elevation of a section of a track with a mine door and the operating means thereto in position looking in the direction indicated by the arrow, the door partly raised; Fig. 2 is a central longitudinal sectional view, the door closed; Fig. 3 is a cross sectional view on 30 the line 3—3 of Fig. 1; Fig. 4 is a detail central longitudinal section of a portion of one of the operating bars and adjustable weights employed in carrying out the invention.

As shown in the drawings, the numerals 1 and 2 represent respectively the cross ties and rails of a section of a railway track. In carrying out the invention the rails on the two sides of the track are arranged to have their joints directly opposite. A suitable upright supporting frame 3 is arranged at each side of the track adjacent the abutting ends of said rails, the purpose of which will be disclosed. The adjacent or abutting ends of said rails are connected to the upper ends of depending members 4 removably connected in any desirable manner at their lower ends to two transverse 40 connecting bars or members 5 arranged transversely under the track below the level of the tops of the cross ties and pivotally connected at their extreme inner or adjacent ends to the vertical downwardly extending portion 6 of a support 7 arranged longitudinally of the track. The outer ends of said connecting bars are adjustably connected by suitable means in one of a longitudinal series of transverse openings or apertures, near the front ends of operating bars or members 8 arranged longitudinally of the track and pivoted at suitable 45 points intermediately of their ends in suitable bearing members 9 mounted on and near the ends of one of the

cross-ties. The front ends of said operating bars or members 8 are adjustably and removably secured by a bolt and link connection 10 or other equivalent means to the lower ends of vertical oppositely disposed bars 60 or links 11 adjustably connected at their upper or free ends in one of a longitudinal series of openings or apertures 12 in horizontally disposed arms or members 13 secured in any suitable manner at their rear ends to the ends of a transverse rock shaft 14 journaled in suitable 65 bearings 15 secured to the upper ends of said upright supporting frames 3. The opposite ends of said horizontally disposed arms or members 13 are connected by links or bars 16 to one of a longitudinal series of transverse openings or apertures 17 in longitudinally 70 disposed door-operating members 18 pivoted near their front ends by bearings 19 to said side supporting frames below said horizontally disposed arms or members 13. The rear or free ends of said arms are secured in any suitable manner to the lower end of a mine door 20 secured at its upper end in any suitable manner above the upper ends of said supporting frames 3. As shown in the drawings, said door is composed of a strip of canvas or other suitable material having a suitable flexibility with a parallel series of transverse slats, but may be 80 made in any suitable form that falls within the scope of the invention.

Weights 21 are adjustably mounted on the pivoted ends of operating bars or members 8 and serve to normally hold the door in a closed position or to close 85 said door after it has been raised by the passage of a train or other wheeled vehicle. Suitable angle bars 22 are arranged longitudinally of the track near the outside of the rails 2 to prevent them from spreading outwardly, while bridles 23 are arranged between 90 said rails to prevent them from spreading inwardly.

In the operation of the invention the train or other vehicle approaching near the mine door causes a depression of the adjacent ends of the rails, which rails through the medium of the depending members 4, 95 impart a downward movement to the outer or free ends of said transverse connecting bars or members 5. As the outer ends of the connecting bars or members 5 are lowered, they carry with them the free ends of said operating bars or members 8, which bars or 100 members, through the medium of the connections described, impart a downward movement to the free ends of said horizontally disposed arms or members 13. As the free ends of said arms 13 move downwardly the free ends of said door-operating members 18 are 105 caused to simultaneously move upward and raise the door to permit of the free passage of the train or other wheeled vehicle running on the track. After the train has passed over the rails 2 said weights 21 act to throw the door-operating mechanism into its initial 110 position, and thereby close the door. The object of providing said door-operating members 18 and

- said arms or members 13 with longitudinal series of perforations or apertures is to secure the proper relative movement of the door with a certain movement of the abutting ends of the rails. 35
- 5 It is thought that from the foregoing description, taken in connection with the drawings, the construction and operation of the invention will be readily understood without requiring a more extended explanation. 40
- 10 Having described my invention, what I claim as new and desire to secure by Letters-Patent, is:—
1. In combination with track rails free for limited vertical movement, transverse connecting members arranged under the adjacent ends of the rails, said members being pivotally connected at their inner ends, means for connecting said members with the rails, longitudinally disposed operating bars pivoted near said rails and connected with the outer ends of the connecting members, a flexible door suspended above and transversely of the rails, longitudinally disposed door operating members pivoted above the rails and connected at their free ends with the lower end of the door, means for connecting the pivot ends of said members with the operating bars and weights adjustably mounted on the frame ends of the operating bars. 45
  2. In combination with track rails free for limited vertical movement, transverse connecting members pivotally connected at their inner ends and arranged under the rails, means for connecting said members with adjacent ends of the rails, longitudinally disposed operating members pivoted near the rails, a flexible door sustained above the rails, longitudinally disposed door operating members pivoted above the rails and connected at their free ends with 50
  3. In combination with track rails free for limited vertical movement, connecting members arranged transversely under adjacent ends of the rails, said members being pivotally connected at their inner ends, means for connecting the rails with said connecting members, longitudinally disposed operating bars pivoted intermediately of their ends near said rails, and connections between the operating bars and outer ends of the connecting members. 55
  4. In combination with track rails free for limited vertical movement, transversely disposed connecting members arranged under the rails, said members being pivotally connected at their inner ends, means for connecting the connecting members with the rails, longitudinally disposed operating bars pivoted near the rails, adjustable connections between the operating bars and connecting members, upright frames arranged at the sides of the rails, a flexible door sustained by the frames, longitudinally disposed door operating members pivoted to the frames and connected at their free ends with the door, a rock shaft journaled between the frames above said door operating members, adjustable connections between the ends of the shaft and pivot ends of the door operating members, adjustable connections between the free and pivot ends of the operating bars and door operating members respectively and weights adjustable on the free ends of the operating bars. 60
- In testimony whereof I have hereunto set my hand in presence of two subscribing witnesses.
- POMPIE LEE ROBERTSON.
